P. NORDLUND

HARNESS BIT

Filed June 2, 1924

Patented Dec. 30, 1924.

UNITED STATES PATENT OFFICE.

PATRICK NORDLUND, OF DODSON, MONTANA.

HARNESS BIT.

Application filed June 2, 1924. Serial No. 717,370.

To all whom it may concern:

Be it known that I, PATRICK NORDLUND, a citizen of the United States, residing at Dodson, in the county of Phillips and State 5 of Montana, have invented new and useful Improvements in Harness Bits, of which the following is a specification.

My present invention pertains to bits for use in harness for horses and mules.

10 The object of my said invention is the provision of a bit that can be readily adjusted for different horses and mules to adapt it to different conditions, and one that is humane and at the same time is calculated to enable a driver with the expenditure of but little effort to control the most fractious animal.

Other objects and practical advantages of the invention will be fully understood 20 from the following description and claims when the same are read in connection with the drawings, accompanying and forming part of this specification, in which:—

Figure 1 is a perspective showing my 25 novel bit as forming part of a harness bridle and as properly applied to a horse.

Figure 2 is a front elevation of the bit per se.

Figure 3 is a sectional view of the bit 30 taken in a plane at right angles to Figure 2.

Similar numerals of reference designate corresponding parts in all of the views of the drawings.

The bridle illustrated includes among 35 other elements cheek straps 1, and to the said cheek straps 1 are appropriately connected bails 2 at the upper ends of the side members 3 of my novel bit. It will also be noticed by comparison of Figures 1 and 3 40 that the said side members 3 of the bit are provided in their rear portions and adjacent to their lower ends with elongated apertures 4 for the appropriate connection of lines or reins 5.

45 The side members 3 of the novel bit may be and preferably are formed of appropriate metal, and each is provided in its upper portion with a transverse aperture 6, and each is also provided below the aperture 6 50 with a longitudinal slot 7 which merges at its upper end into an enlargement 8 preferably of the configuration shown in Figure 3. I would also have it understood that in each side member 3 and spaced apart are

55 apertures 9 that intersect the slot 7 and are adapted to receive one or more screws such as 10 the screw or screws 10 being detachably secured in the side member by the threading of the ends of their shanks in 60 threaded sockets 11 coincident with the apertures 9.

In addition to the side members 3 the bit 65 comprises an upper roller element 12 on a rod 12^a the ends of which are reduced and appropriately secured in the said apertures 6 of the side members 3.

Below the roller member 12 and carried by the side members 3 are upper and lower plate members 13 and 14, all of said members 12, 13 and 14 being preferably formed 70 of appropriate metal, and as illustrated the plate 14 may when desired be confined by the screws 10 in the lowermost portions of the slots 7 of the side members 3; and it will also be noticed that the plate 14 is 75 headed at 15 and is provided at its opposite end with a detachably secured enlargement 16. From this it follows that while there is no liability of the plate member 14 being 80 casually displaced, yet when it is desired to remove the said member 14 the same can be expeditiously and easily accomplished after the screw 17 complementary to the enlargement 16 is withdrawn, and said enlargement 16 is displaced from the member 85 14.

The plate member 13 is headed at 18, and is provided at its opposite end with an enlargement 19 detachably secured in position 90 by a screw 20 or other appropriate means. Consequently when desired said plate member 13 may also be removed from the side members 3. By particular reference to Figure 2 it will be noted that the plate member 13 is provided at 21 with reduced portions which rest and are adapted to rock in the enlargements 8 at the upper ends of the slots 7 but are confined in the said enlargements 8.

100 The member 13 is adapted to play in the enlargements 8.

The plate member 14 when desired can be arranged loosely in the slots 7 so as to be adapted to play, it being understood in this connection that the plate 14 will always be 105 in the lowermost position by reason of gravity. My invention does not contemplate using the members 13 and 14 at one

and the same time, but on the other hand the said members 13 and 14 are used alternately, and when it is desired the member 14 and the member 13 may be adjustably fixed in the side members 3 by the means described.

Experience has demonstrated that it is best to use the member 14 for fractious horses, and that after said member 14 has been used a considerable time, say six months, the member 14 may be removed and the member 13 used in its place.

My novel bit manifestly may be made in different sizes.

The roller member 12 is preferably used at all times and irrespective of whether the member 13 or the member 14 is employed in the bit below the roller member 12.

In the use of the bit with the member 14 relatively arranged as illustrated, it will be manifest that rearward pull on the reins 5 will be attended by movement of the bit calculated to open the mouth of a horse or mule so that the animal can be controlled

with but little effort on the part of a rider or driver.

Having described my invention, what I claim and desire to secure by Letters-Patent, is:—

A bit for the purpose described comprising side members having apertures adjacent to their upper ends and rein receiving apertures in the rear portions of their lower ends, an upper plate member received in the apertures in the upper ends of the side members, said side members having longitudinal slots merged at their upper ends into enlargements adapted to receive and support a lower plate member, the walls of said slots being provided with intersecting apertures, and pins adapted to be received in said last mentioned apertures for securing a lower plate member adapted to be disposed in the longitudinally extending slots.

In testimony whereof I affix my signature.

PATRICK NORDLUND.
